ATTORNEYS

UNITED STATES PATENT OFFICE

GEORGE PAUL BOEHM, OF CHICAGO, ILLINOIS

BATH FIXTURE

Application filed May 20, 1929. Serial No. 364,590.

My invention relates to improvements in bath fixtures, and it consists in the combinations, constructions, and arrangements herein described and claimed.

5 An object of my invention is to provide a bath fixture adapted to be attached to the usual bath constructions, in which means is provided for permitting a bath to be filled with water in such a manner that the usual 10 noise associated with running water is entirely eliminated.

A further object is to provide a device of the type described which is simple in construction and efficient for the purpose intended.

15 Other objects and advantages will appear in the following specification, and the novel features of the invention will be particularly pointed out in the appended claims.

20 My invention is illustrated in the accompanying drawings forming part of this application, in which

Figure 1 is a top plan view, partly in section, of a portion of my invention.

25 Figure 2 is a side elevation, partly in section, of my invention, and

Figure 3 is a slightly modified form of my invention.

In carrying out my invention, I make use 30 of a body portion 1 having leg portions 2 and a boss portion 3. The body portion 1 is provided with a boss 4, see Figure 2. The body portion is provided with a transverse opening 5 as shown in Figure 2. In Figure 2 I

35 have indicated the bottom of a bath by a line 6. The legs 2 rest upon the bottom of the bath, at which time the end of the boss 4 is spaced slightly from the bottom. At this time the flat face 7 is spaced slightly farther from the bottom than the end of the boss. The legs 2 may be provided with rubber pads 8. A tubular member 9 having a central opening 10 and a reduced portion 11 is secured to the body portion 1.

40 In referring to Figure 2, it will be seen that the reduced portion is disposed within the opening 5. The member 9 may be provided with ridges or beads 12 for retaining one end of a flexible tube 13. The opposite 45 end of the tube is secured to an attaching

member 14. The member 14 is adapted to be connected with the water outlet portion of a faucet 15 associated with a bath. Since the member 14 is well known in the art, a detailed description of this unit is not necessary. The member 14 may be easily attached to or detached from the portion 15. The body portion 1 is made from metal, and for this reason is relatively heavy in weight.

55 When the tube 13 is connected with the outlet of the faucet and the water is turned on, the latter will pass through the tube 13 and be conveyed through the opening 5 and discharged upon the bottom of the bath. In view of the fact that the water is discharged 60 upon the bottom relatively near the latter, it will be seen that the noise usually associated with running water is entirely eliminated.

65 The water passing from the body portion 1 flows out from underneath the body portion between the legs. The body portion is sufficiently heavy to remain in a fixed position upon the bottom of the bath. The rubber pads 8 also tend to adhere to the bottom 70 of the bath.

In Figure 3 I have shown a modified form 75 of my device in which a body portion 1' is provided with a bracket 3' for supporting a tube 13'. The lower end of the tube 13' is disposed relatively near the base of the body portion 1' for permitting the water to be 80 discharged upon the bottom of the bath.

I claim:

1. A device of the type described comprising a body portion provided with legs, said body portion being provided with a boss upon the underneath side and an opening passing through the body portion and the boss, liquid-conveying means connected with said body portion and communicating with the opening therein, and means associated with said liquid-conveying means and adapted to be removably attached to a faucet.

2. A bath fixture comprising a body portion provided with a plurality of legs, said body portion being provided with an opening therethrough terminating relatively near the bottom of a bath when said body portion is disposed therein, a tubular member secured 100

to said body portion and having an opening communicating with the opening in said body portion, a flexible tube having one end secured to said tubular member, and means secured to the opposite end of said flexible tube and adapted to be removably attached to a faucet.

3. A bath fixture comprising a body portion provided with a plurality of legs, said body portion being provided with an opening therethrough terminating relatively near the bottom of a bath when said body portion is disposed therein, a tubular member secured to said body portion and having an opening communicating with the opening in said body portion, a flexible tube having one end secured to said tubular member, means secured to the opposite end of said flexible tube and adapted to be removably attached to a faucet, and pads secured to said legs.

Signed at Chicago in the county of Cook and State of Illinois this 14th day of May, 1929.

GEORGE PAUL BOEHM.
